SPOUT FOR ATTACHMENT TO THE NECK OF A CONTAINER

John M. Warner, 940 Circle Drive, Elm Grove, Wis.

Filed Aug. 28, 1963, Ser. No. 76,376

Term of patent 7 years

(Cl. D58—26)

FIG. 1 is a spout for attachment to the neck of a container, showing my new design;

FIG. 2 is a side elevation thereof;

FIG. 3 is a bottom plan view thereof;

FIG. 4 is an end elevational view thereof taken from the top of FIG. 1; and

FIG. 5 is an end elevational view thereof taken from the bottom of FIG. 1.

I claim:

The ornamental design for a spout for attachment to the neck of a container, substantially as shown.
